UNITED STATES PATENT OFFICE

PHILIP MUELLER, OF DECATUR, ILLINOIS, ASSIGNOR, BY MESNE ASSIGNMENTS, TO MUELLER CO., OF DECATUR, ILLINOIS, A CORPORATION OF ILLINOIS

CHINA SPOUT

Application filed January 15, 1927. Serial No. 161,424.

The present invention relates to fluid supply fixtures, such as spouts and faucets, which are made from china or ceramic material, and has to do more particularly with an improved connection, whereby such fittings may be conveniently connected with water supply pipes.

The invention of this application is a variation of the connection disclosed in my co-pending application, Serial No. 149,740, filed November 20, 1926, in which the generic claims are incorporated.

As is well known, spouts of ceramic material are liable to crack or fracture, and it is not practicable to thread or similarly form the same for direct connection with the water supply pipe. Moreover, it is desirable to avoid direct contact between the ceramic material and the metal connections, since the two materials are variably expansible, and, moreover, the unyielding character of the connections renders the same liable to fracture the spout when tightened.

An object of the invention is to provide a connection which will enable the ceramic spout to be fixedly positioned without danger of breakage, and which will also permit final positioning of the spout after the connections are tightened, to properly direct the same with reference to the tub or basin to which it delivers. It is often necessary to give the spout a final movement after the connections are tightened, and it is desirable to accomplish this without loosening the latter. The present invention has as an object the provision of a connection which will permit this adjustment.

A further object of the invention is to provide a connection in which there is no direct contact between the metallic parts of the connection and the spout or other ceramic filling.

Other objects of the invention relate to simplicity of construction, convenience in assembling, and facility of operation, and will become apparent as the description proceeds.

The invention comprises broadly, a spout construction having a bore adapted to receive and hold against rotation a flexible gasket or

other element which is relatively soft or yielding as compared to metal. Preferably, the gasket is also held against movement longitudinally of the spout. Within the bore is positioned a metallic sleeve, which would be freely rotatable, and otherwise movable in the spout, except for the gasket which engages the sleeve, as by receiving the latter in an aperture formed therein. The sleeve snugly fits into the gasket, and thereby is held against independent rotation, and also it is preferred, although not necessary, against movement longitudinally of the spout.

The sleeve is threaded or formed in any equivalent manner for engagement with the supply pipe, and being held fixed in the spout by means of the gasket, it may be rotated by turning the spout, and thereby tightened upon the supply pipe. Rotation of the spout about the supply pipe imparts corresponding rotation to the sleeve, and the latter, when the spout reaches a fixed abutment such as a wall, presses the gasket against a wall of the spout, thereby locking the latter in position.

The bore of the spout around the gasket tapers toward the rear end of the spout, and, preferably, the periphery of the gasket is correspondingly formed to effect a watertight seal. After the end of the spout engages a wall or other fixed abutment continued rotation of the same forces the gasket rearwardly, due to the fact that travel of the sleeve along the supply pipe continues. The spout is thus clamped against the wall, and due to the taper of the spout bore, the gasket is compressed radially inwardly producing a watertight seal at the periphery of the gasket, and around the sleeve.

Preferably, the engagement between the spout and gasket is a frictional one, so that the final adjustment of the spout to direct the same properly toward the basin, tub, or other fixture, with which it is used, may be accomplished without releasing the connection. These, and other features of the invention will become clearer as the description proceeds in connection with a preferred form illustrated in the accompanying drawings, wherein:

Figure 1 is a vertical longitudinal sectional view.

Figure 2 is a fragmentary vertical longitudinal sectional view of the rear end of a 5 spout with a portion of the connection therein.

Figure 3 is a view similar to Figure 2 with the entire connection positioned and assembled within the spout and the latter about to 10 be positioned upon a supply pipe.

Figure 4 is a view similar to Figure 3 of a modified form of connection.

Figure 5 is a fragmentary sectional view of another modification.

15 Figure 6 is a fragmentary vertical sectional view of a still further modification.

Figure 7 is a longitudinal sectional view of the sleeve illustrated in Figures 1 to 6 inclusive.

20 Figure 8 is a transverse section on the line 8—8 of Figure 7.

Figure 9 is a longitudinal sectional view of a modified form of connection sleeve.

Figure 10 is a transverse section on the line 25 10—10 of Figure 9.

Figure 11 is a longitudinal sectional view of another form of sleeve.

Figure 12 is a transverse section on the line 30 12—12 of Figure 11.

Figure 13 is a longitudinal sectional view of another form of sleeve with a modified gasket thereon.

Figure 14 is a transverse section on substantially the line 14—14 of Figure 13.

35 Figure 15 is a longitudinal vertical sectional view showing the use of the connection with a nipple which may be subsequently connected with a supply pipe to form a part thereof.

40 Figure 16 is a longitudinal section of a modified form of the sleeve illustrated in Figure 4.

Referring to the drawings for a more detailed description, 10 indicates a china or 45 ceramic fitting, conventionally illustrated as a spout, having a bore 11 enlarged at its rear end to form a chamber 12. The bore of the spout at the chamber 12 tapers from a shoulder 13 toward the rear end of the spout. That 50 is to say, the wall 14 of the chamber converges toward the rear opening 15. The chamber, as thus formed, constitutes a seat for a flexible gasket 16 of material which is soft or yielding as compared to metal, and may be, 55 for instance, rubber. The gasket may be inserted into the chamber 12 through the rear opening 15 by flexing the same, and when it enters the chamber, it will expand as illustrated in Figure 2, and closely fit in the spout.

60 The periphery of the gasket is preferably inclined to correspond to the inclination of the chamber wall 14, and since the gasket is formed for the close fit illustrated, it will be held against free rotation, due to the frictional engagement between its periphery and

the wall 14. Furthermore, it will be held against free longitudinal movement not only by the frictional engagement, but also by abutment of one face with the shoulder 13.

After insertion of the gasket into its seat, a 70 metallic sleeve 17 threaded internally to fit upon the supply pipe S extending through the wall W, may be inserted into the chamber, and into the central opening 16' of the gasket. It may be explained that the wall W is simply 75 illustrative of any fixed element, such as a portion of a tub, basin, or even a wall or partition of a building against which it is not unusual to position a supply spout in the more modern installations.

Referring to the metallic sleeve 17, the same 80 has a bevelled forward end 18 which facilitates insertion of the sleeve into the gasket, and it is of a sufficient size to fit closely within the opening 16' of the gasket. On its periphery, the sleeve has two spaced flanges 19, 20; the former is at the forward end of the sleeve, and may be provided, if desired, with means such as corrugations 20', adapted to positively interlock with the gasket, and thereby assist the relatively tight fit of the gasket bore with the sleeve in preventing rotation of the sleeve within the gasket.

The sleeve and gasket as thus positioned 85 within the spout (Figure 3) constitute a complete assembly to be mounted upon the supply pipe S. The sleeve is connected with the spout through the gasket because of the frictional engagement of the sleeve with the gasket, and the positive engagement of the 100 corrugations 20', if used. Independent rotation of the sleeve will not occur, and the tight fit of the gasket in its seat will prevent rotation of the gasket in the spout. Consequently, by positioning the spout upon the 105 supply pipe S, and rotating it, the sleeve will be threaded upon the supply pipe, and continued rotation of the spout, after its rear end engages the wall W, will cause the sleeve to continue its travel along the supply pipe, thereby pressing the gasket toward the rear 110 end of the spout. Due to the tapering bore of the spout around the gasket, the latter will be compressed as it is forced rearwardly in the spout by the flange 19 of the rotating 115 sleeve to clamp the spout against the wall and the final position of the parts is substantially as illustrated in Figure 1. It will be observed that there is effected a sufficient compression of the gasket to insure a watertight seal at its periphery, and this compression being transmitted inwardly, also affords a water-tight seal around the sleeve at the central opening 120 in the gasket.

When the parts of the connection are finally tightened, it may be found desirable to 125 give a partial revolution to the spout to properly direct it with reference to the tub or basin with which it is set up, and this may be accomplished without releasing the joint or 130

danger of breaking the spout simply by applying sufficient force to overcome the frictional engagement between the gasket and spout, and around the latter.

Referring to Figure 4, there is shown a somewhat modified construction in that the spout at its rear end is counter-sunk, as at 21, to provide a seat for a second and bevelled gasket 22 which is interposed between the rear of the spout and the wall W. This gasket closely surrounds the supply pipe S, and being gripped between the wall and the spout, assists the gasket 16 in preventing leakage. Furthermore, it may be engaged and compressed, as illustrated by the rear end 17' of the sleeve 17'', which differs from the sleeve 17 of Figures 1 to 3, in that the rear flange 20 of the former figures is omitted. In assembling this construction the sleeve 17'' is inserted into the spout before the gasket 16, and after the latter is introduced, the sleeve is drawn into the opening in the gasket. In all other respects, the construction corresponds to that illustrated in the form of Figures 1 to 3.

In Figure 5, there is illustrated another modification which corresponds to that shown in Figure 4 in all respects, except that a seat 23 is provided for a gasket 24, the walls of the gasket and seat being at substantially right angles to one another instead of inclined as in Figure 4.

In the form of Figure 6, in which a sleeve 25, similar to the sleeve 17 of Figure 1 is employed, and is provided additionally upon its rear flange 26, with means, such as the rib 27, to interlock with a second gasket 28 interposed between the flange and the wall W. This gasket, as illustrated in Figure 6, is not extended upwardly into a seat formed in the spout as in Figures 4 and 5, although, obviously, this variation would not be a departure from the invention. The gasket 28 closely surrounds the supply pipe S, and when compressed by the flange 26 of the sleeve 25, assists the gasket 16 in preventing leakage.

Figures 9 to 14 inclusive, show modified forms of connection sleeves which may be substituted for the sleeves illustrated in Figures 1 to 6.

Referring to Figure 9, the sleeve 29 lacks means upon the flange 30 for positive engagement with the gasket, but such means as the corrugations 32, is provided upon the portion of the sleeve between the flange 30, and the end flange 31.

In the form of the invention illustrated in Figures 11 and 12, the sleeve 33 has means for positively engaging the gasket upon the inner face of flange 34, such means being the ribs or corrugations 35. Similar corrugations 36 are provided upon the portion of the sleeve which fits within the gasket.

In Figures 13 and 14, there is illustrated

another form of sleeve in which the portion of the sleeve 37 which fits within the gasket 38 is formed with a plurality of longitudinally extending keys or ribs 39, which fit closely in suitable key-ways 40 which are pre-formed in the gasket 38, and insure rotation of the sleeve with the gasket when the latter is rotated by the spout.

Referring to Figure 15, a ceramic or china spout 41 of slightly different form from that illustrated in Figure 1 is shown as fixedly attached, by means of the connection described, to a threaded nipple 42, which may be in turn threaded into a supply pipe. The sleeve 43 and gasket 45 correspond to similar parts illustrated in Figure 4, and a metal plate or flange 46 is rotatably mounted upon the shank for adjustment thereon. This plate serves as an abutment for the spout in tightening the connection. A second gasket 47 surrounds the plate 46 and projects rearwardly from the spout a greater distance than the plate in order to abut the wall of any fixture to which the spout may be applied. It will be observed that both the plate 46 and gasket 47 are arranged in a seat 48 counter-sunk in the rear end of the spout.

In Figure 16 there is shown a slight modification of the sleeve 17'' illustrated in Figure 4. As will be observed, the periphery 49 of the sleeve 50 is tapered for a substantial distance and preferably from the end of the sleeve to the flange 51. This construction facilitates the insertion of the sleeve into the rubber gasket 16 (Figure 4).

The connection described is particularly useful with ceramic spouts, and other fittings of frangible character, since there is no direct contact between the metal connections and the ceramic material. Moreover, it is unnecessary to form the spout with threading, key-ways, or other connecting means of any character for engagement with the metallic parts, and thus the construction of the spout for use with this connection is not difficult.

It will be understood, of course, that the invention is not limited to the precise structural details illustrated and described, and where such terms as "spout," "gasket" and "sleeve" are employed, to designate conventionally constructed parts, they are to be interpreted as covering any equivalent means accomplishing the desired result. For instance, the invention is useful with any ceramic water supply fitting, such as spray heads, faucets, and the like.

I claim:

1. In combination with a pipe, a ceramic spout, a metallic sleeve in said spout threaded for connection with the pipe, a gasket held in said spout against rotation, said gasket serving to hold the sleeve against rotation relative to the spout and the sleeve being ad-

- justable on the pipe through rotation of the gasket by the spout, said spout having its bore around said gasket tapering toward the rear of the spout, the gasket being forced rearwardly in said spout by the sleeve as the latter is adjusted on said pipe.
2. In combination with a pipe, a ceramic spout, a metallic sleeve in said spout threaded for connection with the pipe, a gasket held frictionally in said spout against rotation, said gasket serving to hold the sleeve against rotation relative to the spout and the sleeve being adjustable on the pipe through rotation of the gasket by the spout, said spout having its bore around said gasket tapering toward the rear of the spout, the gasket being forced rearwardly in said spout by the sleeve as the latter is adjusted on said pipe.
3. In combination with a pipe, a ceramic spout, a gasket in said spout held against rotation, the spout around said gasket having a bore tapering toward the rear end of the spout, said gasket being compressible when forced in the direction of said taper, a metallic sleeve threaded for connection with the pipe in said spout fitted into said gasket and connected only through the latter with said spout to be rotated thereby relative to the pipe, said sleeve having means engaging said gasket and effecting an interlocking engagement therewith.
4. In combination with a pipe, a ceramic spout, a gasket in said spout held against rotation, the spout around said gasket having a bore tapering toward the rear end of the spout, said gasket being compressible when forced in the direction of said taper, a metallic sleeve threaded for connection with the pipe in said spout fitted into said gasket and connected only through the latter with said spout to be rotated thereby relative to the pipe, said sleeve having outwardly projecting means engaging said gasket and effecting an interlocking engagement therewith, and a peripheral flange abutting a face of said gasket to force the latter rearwardly in the spout as the sleeve is adjusted on the pipe.
5. In combination with a supply pipe extending through an opening in a wall, a ceramic spout, a metallic sleeve in said spout threaded for connection with the supply pipe, a gasket held in said spout against rotation, said gasket serving to hold the sleeve against rotation in the spout and the sleeve being adjustable on the supply pipe through rotation of the gasket by the spout, said spout having its bore around said gasket tapering toward the rear of the spout, the gasket being forced rearwardly in said spout by the sleeve as the latter is adjusted on said supply pipe, and a second gasket around the supply pipe between the rear end of said sleeve and said wall through which the pipe extends.
6. In combination with a supply pipe extending through an opening in a wall, a ce-

ramic spout, a metallic sleeve in said spout threaded for connection with the supply pipe, a gasket held in said spout against rotation, said gasket serving to hold the sleeve against rotation in the spout and the sleeve being adjustable on the supply pipe through rotation of the gasket by the spout, said spout having its bore around said gasket tapering toward the rear of the spout, the gasket being forced rearwardly in said spout by the sleeve as the latter is adjusted on said supply pipe, and a second gasket around the supply pipe between the rear end of said sleeve and said wall through which the pipe extends, and gripped upon said wall at one side and the spout and sleeve at the other side.

7. In combination with a conduit, a ceramic spout, yieldable means adjustable upon said conduit and rotatable with said spout, said yieldable means forming the sole support of said spout upon said conduit, and supporting said spout entirely free of contact with any part of said conduit, and means for causing said yieldable means to be contracted radially as it is rotated only by said spout to form a liquid-tight joint with said spout and pipe.

8. In combination with a conduit, a ceramic spout having a portion of its bore tapering toward the rear thereof, and yieldable means engaging said tapered portion of the spout to be rotatable therewith and being adjustable upon said conduit, said yieldable means forming the sole support of said spout on said conduit and supporting said spout entirely free of contact with any part of said conduit, and being contracted radially by said tapered portion of the spout upon rearward movement of said means upon said conduit.

9. A ceramic spout having a bore provided with a shoulder, a yieldable gasket larger than said bore held therein and having an opening, a sleeve projected through said opening and held by said gasket in spaced relation to said spout, said sleeve having means to facilitate insertion thereof through said opening in said gasket.

10. A ceramic spout having a bore provided with a shoulder, a yieldable gasket larger than said bore held therein and having an opening, a sleeve projected through said opening and held by said gasket in spaced relation to said spout, said sleeve having a tapered nose facilitating insertion of the sleeve into said opening, and a shoulder on said sleeve for abutment with the gasket.

In testimony whereof I have hereunto set my hand.

PHILIP MUELLER.
